CANDLE HOLDER

Marcus A. Peiser, Chicago, Ill.
(1110 Hull Terrace, Evanston, Ill.)

Filed Sept. 9, 1959, Ser. No. 839,026

7 Claims. (Cl. 67—23)

This invention relates to candle holders and, more particularly, to a novel holder capable of holding candles of various diameters, or of any geometric shape or size, which can be adapted for adjustment to fit into candlestick sockets of various diameters and slopes and which is self-conforming to candle sockets having conical side walls.

A primary object of the invention is to devise a candle holder such as above described which is simple and economical in construction, attractive in appearance, and capable of long life in service.

A more specific object of the invention is to form the holder from a single slotted blank of stainless steel or other suitable material, such as plastic, rolled or otherwise formed into a pair of split annuli interconnected by a segment of said blank defining a neck, one of the annuli adapted to hold candles of various diameters and the other of said annuli adapted for reception within candlestick sockets of various diameters and shapes.

Another object of the invention is to devise a candle holder such as above described in which the separate annuli are formed of a material whereby each annulus can be manually adjusted to various diameters independently of the other and wherein both annuli are resilient at any selected diameter to grip either a candle or a candle holder or fixture.

Another object of the invention is to provide lugs on the top of the candle holding annulus or body so that the latter can cut and grip the base end of a candle.

Still another object of the invention is to provide slots in the lower edges of the bottom annulus which is defined by spaced feet connected by the neck to the upper annulus or body of the candle holder. These slots enable the feet to conform to and resiliently grip the sloping side walls when the feet are urged into a conical socket.

Yet another object of the invention is to form the feet in the shape of a downwardly tapered cone to facilitate the gripping action thereof.

The foregoing and other objects and advantages of the invention will become apparent from a consideration of the following specification and the accompanying drawings, wherein:

Figure 1 is a plan view of a blank which may be formed into the novel candle holder;

Figure 2 is a top plan view of a preferred embodiment of the novel candle holder;

Figure 3 is a side elevational view thereof;

Figure 4 is a front elevational view thereof;

Figure 5 is a side elevational view of a modified holder in which the feet which define the lower split annulus are provided with a coating of a material such as synthetic plastic which will increase adherence to a candle stick;

Figure 6 is a view similar to Figure 5 showing the modified candle holder with its lower annulus positioned in the socket of a candle stick with sloping sides.

Figure 7 is a view similar to Figure 6 showing a candle

2

positioned within the candleholder and in a socket with sloping sides.

Figure 8 is a view similar to Figure 3 showing another modification of the invention.

Figure 9 is a view similar to Figure 7 showing a candle positioned within the candleholder and in a socket having cylindrical sides.

Describing the invention in detail and referring first to Figure 1 which shows a flat metal stamping 2 from which

the novel candle holder is formed, it will be seen that the stamping comprises a body 4 having a plurality of upstanding lugs or ears 6. The body 4 is connected by a neck 8 to spaced feet 10 separated from each other by a slot 12 which preferably extends upwardly into the neck.

The upper edges of the feet 10 slope downwardly as at 14 from the overlying edges of the body 4 for a purpose hereinafter described. Also, the lower edges of the feet 10 are slotted, as at 16, the slots 16 preferably being approximately parallel to the slot 12 but being shorter than the slot 12.

It will be understood that the stamping 2 is formed of any desired material such as steel or plastic which can be manually deformed to a desired shape but which is resilient in any permanently deformed condition thereof, such as that shown in Figures 2-4, wherein it will be seen that the body 4 and the feet 10 have been rolled or otherwise deformed to substantially annular shapes as seen in the plan view of Figure 2.

Thus the body 4 in its finished form, shown in Figure 2, is a split annulus divided by a substantially vertical slot 18 (Figure 2) which is defined by opposite ends 20 (Figure 1) of the body 4.

The feet 10 in their finished form also are in the shape of a split annulus divided by a slot 22 (Figure 2) which is defined by corresponding ends 24 (Figure 1) of the feet 10.

Figures 5-7 show a modification of the novel candle holder wherein the feet are covered by a coating 27 of material such as rubber, plastic, or adhesive tape.

As best seen in Figure 3, the feet 10 are cylindrical but when urged into the sloping sides of the candle socket 28 of a candlestick 30, they take on the shape of a downwardly sloping cone, as shown in Figure 7, to grip the sloping side walls of said socket 28, thereby securely retaining the candle holder 4 and the candle 26 in said socket.

The lugs 6 tend to shape, confine and grip the candle in the candle holder above the feet 10; however, if desired, the lugs 6 may be omitted, as shown in the modification of Figure 8.

It will be understood that an important feature of the invention are the slots 16 in the lower edge of the feet 10 and the manner in which they are connected to the body 4 by the neck 8 so that the feet, which are resilient, may contract along their lower edges to grip the candle socket 28 as the feet 10 and candle 26 are urged into the candle socket 28.

The angularity of edges 14 with respect to the bottom of the body 4 is preferably of the order of ten to fifteen degrees. This novel construction permits the novel candle holder to adapt itself to the conical shape of the sockets in modern styled candlesticks, as made of glass, plastic, ceramic and the like. The lower edges of the feet 10 form fingers between the slots 16 so that the fingers may grip the candle socket as heretofore described.

After the feet 10 have been inserted into the conical socket 28, the angularity between the upper edges 14 of the feet 10 and the lower edge of the body 4 is reduced proportionately as the feet are deformed to conical shape as shown in Figure 6.

This novel construction permits the feet to adjust themselves to a socket 28 tapered at an angularity of up to the order of fifteen degrees from a cylindrical configuration.

Thus, it will be understood that the novel holder is capable of supporting candles of greatly varying diameters and is capable of support by almost any candlestick of conventional size and shape. Moreover, the novel holder is attractive in appearance, is neat, compact, and lightweight, and can be quickly adjusted to various sizes of candles and candlesticks. It should also be noted that the novel holder is capable of long life in service even after a great many manual adjustments such as heretofore described.

While the present invention has been explained and described with reference to specific embodiments of structure, it will be understood, nevertheless, that numerous modifications and variations are susceptible of being incorporated without departure from the essential spirit or scope thereof. For example, the said candleholder may be made of a single sheet of plastic material shaped or extruded through a die. Accordingly, it is not intended for an understanding of this invention to be limited by the specific foregoing description nor by the illustrations in the annexed drawings, except as indicated in the hereinafter appended claims.

What is claimed as new and desired to be secured by Letters Patent of the United States is as follows:

1. A candle holder comprising a body in the form of an axially upright vertically split annulus the vertical edges of which are separated to form a vertical slot, a pair of axially upright semi-annular feet having their corresponding ends spaced to define a substantially vertical slot aligned with the first-mentioned slot, a neck joining said feet to said body, said feet being separated by a slot extending into said neck, and a plurality of slots in said feet extending upwardly from their lower edges.

2. A candle holder according to claim 1 wherein the upper edges of said feet diverge downwardly from said neck with respect to the lower edges of said body at opposite sides of said neck.

3. A candle holder formed of a single sheet of resilient material and having a body in the form of an axially upright vertically split annulus the vertical edges of which

are separated to form a slot, a pair of axially upright parti-annular feet separated by a slot, a neck connecting said feet to said body, said feet having upper edges diverging downwardly toward corresponding ends of the feet, and a plurality of slots in said feet extending upwardly from their lower edges.

5. A candle holder comprising a body in the form of an axially upright vertically split annulus the vertical edges of which are separated to form a vertical slot, a pair of axially upright semi-annular feet having their corresponding ends spaced to define a substantially vertical slot aligned with the first mentioned slot, a neck joining said feet to said body the upper edges of said feet diverging downwardly from said neck with respect to the lower edges of said body at opposite sides of said neck, a slot extending into said neck separating said feet and a plurality of slots in each foot extending upwardly from their lower edges.

10. A candle holder as in claim 4 wherein the feet are coated with a resilient coating covering said slots.

20. A candle holder formed of a single sheet of resilient material and having a body in the form of an axially upright vertically split annulus the vertical edges of which are separated to form a vertical slot, a pair of axially upright parti-annular feet separated by a slot, a neck connecting said feet to said body, said feet having upper edges diverging downwardly from the facing lower edges of said body at an angularity of substantially 15 degrees to accommodate insertion of the feet into a conical socket of a holder, a plurality of slots in said feet extending upwardly from their lower edges, the last mentioned slots being substantially parallel to but shorter than the slot separating said feet, the said feet being adapted to be deformed to conical shape when inserted in the holder.

25. A candle holder as in claim 6 wherein the body is formed with a plurality of upstanding lugs to grip and hold the candle.
